ADOLPH PEARL, OF NEW YORK, N. Y.

Letters Patent No. 83,088, dated October 13, 1868.

IMPROVEMENT IN DAMPING-APPARATUS FOR COPYING-PRESSES.

The Schedule referred to in these Letters Patent and making part of the same.

To all whom it may concern:

Be it known that I, ADOLPH PEARL, of the city, county, and State of New York, have invented a new and improved Apparatus for Dampening Paper for Copying; and I do hereby declare that the following is a full, clear, and exact description of the same, reference being had to the accompanying drawings, forming a part of this specification.

The object of this invention is to provide for the more uniform dampening of paper for copying letters and other manuscripts; and the invention consists, firstly, in a leather-covered roller, carried within a suitable yoke, in combination with a capillary cushion, projecting from a water-bath, whereby a means is provided for a uniform dampening of the said roller.

Figure 1 represents a plan view of my improved apparatus for dampening paper, as illustrated, with the lid or cover open, and

Figure 2 a transverse section of the same, illustrating the manner of operating the roller upon the cushion.

Similar letters of reference indicate corresponding parts in both figures.

Referring to the accompanying drawings A, is a box or case, constructed of tin-plate, or other suitable material, of an elongated formation, and having its interior divided into two compartments by means of a partition running lengthwise of the said box A.

B is a roller, of cylindrical formation, constructed of wood, or other suitable material, and having its periphery covered with India rubber, or other suitable elastic material, and, lastly, one or more layers of chamois-leather, or other absorbent material, cut in strips, and passing spirally or otherwise around the said periphery from one extremity thereof to the other. This roller B is hung to turn freely within suitable bearings, carried upon the extremities of a yoke, C, which is provided centrally with a handle, c, for manipulation thereof, substantially after the manner of the ordinary blotting-roller.

D is a cushion, of elongated formation, and of a length corresponding with that of the roller B. This cushion D is composed preferably of a cloth exterior

and woollen filling, but may be composed of any other suitable materials, and secured by means of tacks, or otherwise, upon the upper side of a block, d, of wood or other material, of the same longitudinal and lateral dimensions thereof.

Pending from the extremities of the cushion D are conduits e, which may be composed of buckskin, cloth, or other porous substance, suitable for conduction of water by capillary attraction.

The block d of the cushion D is placed within the larger of the two compartments of the box or case A, which forms a water-bath, so that the upper surface of the cushion D will reach to about level with the upper edge of the said bath, and the said bath is filled about half full of water, so that the lower extremities of the conduits or pendants e are submerged therein.

The smaller or other compartment of the case or box A is intended to receive the roller B when not in use.

In the operation of this invention, the roller B is held by the handle c of the yoke C, as illustrated in fig. 2, and caused to pass back and forth upon the cushion D, which, after having been moistened by pouring water over it, is kept moist by the capillary action of its conduits or pendants e, and by said contact of the roller thereon, moisture is readily imparted therefrom to said roller.

When the roller has been thus moistened, it is rolled over the paper, to which it imparts the proper degree of moisture uniformly all over the surface, obviating the danger of blotting and smearing which results from the use of a brush.

What I here claim as my invention, and desire to have secured by Letters Patent, is—

The combination of the leather-covered dampening-roller B, the moistened cushion D, and the water-bath in the case A, substantially as described, and for the purpose herein set forth.

ADOLPH PEARL.
